TRAIN CONTROL SYSTEM

Filed April 8, 1925

UNITED STATES PATENT OFFICE.

GEORGE W. DODGE, OF KNOXVILLE, TENNESSEE.

TRAIN-CONTROL SYSTEM.

Application filed April 8, 1925. Serial No. 21,600.

To all whom it may concern:

Be it known that I, GEORGE W. DODGE, a citizen of the United States, residing at Knoxville, in the county of Knox and State of Tennessee, have invented certain new and useful Improvements in Train-Control Systems, of which the following is a specification.

The invention relates to train control systems, particularly of the type known as the union switch and signal system, and has for its object to provide in combination with a system of this character indicating means, preferably audible, for notifying the engineer, after he has entered restricted territory, that he has brought the train within the speed limit imposed on him while in said restricted territory, and to warn him when the speed of his train approaches the speed limit under which he is running.

A further object is to provide means whereby if the speed of the train reaches the speed limit or approaches too closely the speed limit, the brakes will be automatically set and the train stopped or reduced in speed.

A further object is to provide in combination with the magnet valve, spaced ports carried by a slide valve controlled by the magnet, and a speed controlled slide valve having spaced ports, pipe connections in communication with the timing valve and blow down reservoir, and the main air feed pipe line, whereby, when the speed controlled valve is in a predetermined position, under the speed controlling mechanism a signal will be given to the engineer that he is traveling at the predetermined speed and must not increase his speed, as an increase of speed will allow exhaust of air from the pipe, leading to the relay and protection valves and cause the automatic setting of the brakes.

A further object is to provide the speed controlled valve with spaced ports, said ports being positioned whereby when the valve is in operative position, substantially at a predetermined speed, one of said ports will register with spaced ports in communication with a signalling device and the feed line, and the other port in communication with a port leading to the atmosphere, and in a position where upon a further movement of the valve a port leading to the re-

lay and protective valves will be uncovered. Also to provide the magnet control valve with spaced ports which, when the train is in a restricted area or territory and the magnet in deenergized position, will register with spaced ports in the timing valve and blow down reservoir pipe line, and allows a continuous exhaust from the blow down reservoir while the train is in restricted territory. The magnet valve has its other port, when the valve is deenergized, in registration with spaced ports in the feed line when the train is in restricted territory, thereby allowing flow of air through the port in the speed control valve to the signalling or indicating means within the engine cab, for operating the signalling means, when the train is traveling at substantially the predetermined speed.

With the above and other objects in view the invention resides in the combination and arrangement of parts as hereinafter set forth, shown in the drawing, described and claimed, it being understood that changes in the precise embodiment of the invention may be made within the scope of what is claimed without departing from the spirit of the invention.

Referring to the drawing wherein the single figure shows a diagrammatic view of the device, parts being shown in section to better illustrate the same, the numeral 1 designates an engine axle, or any other rotatable part of an engine, and which axle is provided with a bevelled gear 2, which meshes with a bevelled gear 3 carried by a vertically disposed flexible shaft 4, which operates the centrifugal governor 6 through the gears 7 and 8, which connect the governor to the flexible shaft 4. The centrifugal governor, during its rotation, causes the arms 9 thereof to pivot outwardly incident to the centrifugal force, and the weights 10 carried thereby, and causes the rollers 11, carried by the inner ends of the arms, to move forwardly in engagement with the disc 12 of the slidable bar 13, which is slidably mounted in the bearing 14 against the action of the coiled spring 15, which normally forces the disc 12 rearwardly, therefore it will be seen that as the speed of the axle 1 increases or diminishes the amount of movement of the bar 13 will in-

crease or diminish. All of the above structure is the governing portion of the device and is common in the system above referred to, an example of which system is shown in 5 Patent No. 1,299,753 issued to Nevens, et al, dated April 8th, 1919. Slidable bar 13 is provided with a plate 16, in which are adjustably mounted speed regulating bolts 17, 18 and 19. The adjustable bolt 17 co- 10 operates with the valve stem 20 of a conventional form of blow down valve 21, which blow down valve operates in the usual manner as in systems now in use and particularly in the system set forth above. The adjustable bolt 19 cooperates with the protection valve 22 in the usual manner and operates the same as set forth in the system referred to, and all of which structure is old in the art.

20 Slidably mounted within the valve casing 23 is a speed control valve 24, which speed control valve is provided with a stem 25, which is normally held in engagement with the speed regulating adjusting bolt 18 by 25 means of the coiled spring 26, which is interposed between the valve 24 and the wall 27 of the valve casing, therefore it will be seen when the adjusting bolt 18 is moved towards or away from the valve, the valve 30 24 may be adjusted to various positions according to the desired limit of speed, that is when the train is within restricted territory, and the magnet valve 28 is in deenergized position, as shown in the drawing, however 35 under normal conditions, when the train is not in restricted territory, the valve 24 has freedom of movement under the control of the governor and the coiled spring 18. The magnet valve 28 is slidably mounted in a 40 casing 29, and is controlled by means of a magnet 30, which magnet is deenergized when the train enters restricted territory, and is energized when the restrictions are lifted, and may be controlled through any 45 suitable electric control system, which system forms no part of the present invention. Magnet valve 28, when the magnet 30 is de- 50 energized, is forced to the position shown in the drawing by means of the coiled spring 31 where its elongated port 32 will register with the ports 33 in the valve casing 29, and in which ports 33 the feed pipe 34 and the pipe 35 are connected, therefore it will be 55 seen that when the magnet valve is in the de-energized position, air from the feed line or pipe 34 will pass through the port 32, and thence through the pipe 35, and which pipe is connected at its other end in the port 36 of the control valve casing 23. Dis- 60 posed in the control valve casing 23 adjacent the port 36 is a second port 37, in which is connected a discharge pipe 38, which may lead into the engine cab, and is provided with a signalling device 39 which 65 is operated in any suitable manner, and

which may be of any type, however it is preferably an audible type, for instance a whistle. The speed control valve 24 is provided with an elongated port 40, which port, when the speed control valve is adjusted to a predetermined speed, for instance twenty miles, when the train is in restricted territory, registers with the ports 36 and 37. It will be seen that when the magnet valve 28 is in deenergized position, as shown in the drawing, and the train in restricted territory, air from the feed line 34 will pass through the port 32 of the magnet valve, pipe 35 into the port 40 of the speed control valve 24 and thence through the pipe 38 to 70 the audible signal 39. Speed control valve 24 is provided with a second elongated port 41, which port 41 is in communication with a port 42 which leads to the atmosphere 75 through a pipe 43. The port 41 terminates adjacent a port 44 in the casing 23 and in which port 44 is connected a pipe 45, which leads to the relay and protection valves, therefore it will be seen, assuming the valve 24 has been previously adjusted and set for 80 a predetermined speed, for instance twenty miles, per hour, as long as this speed is substantially maintained the port 40 will register with the ports 36 and 37 and the audible signal 39 will be operated, thereby indicating to the engineer if he increases his speed, the speed control valve will move in the direction of the arrow a, which will cause the ports 44 and 42 to register with the valve port 41, thereby allowing exhaust of air 85 from the relay and protection valve pipe 45 to the atmosphere through the pipe 43, and which exhaust of air will cause an automatic application of the brakes. It will be 90 seen that the engineer, to protect the pressure in the relay and protection valve line 45 will have to stay within the restricted speed limit, however he will have a free range of speed below the prescribed and established speed within the restricted area.

Magnet valve 28, when in normal position, and when the train is not in a restricted area, is held down by the magnet 30, and at which time the elongated port 32 will 115 register with the port 33, in which is connected the feed pipe 34, and with the port 46, in which is connected the pipe 47, which leads to the timing valve and blow down reservoir, therefore it will be seen that under 120 normal conditions, when the train is not in restricted area, pressure will be supplied to the blow down reservoir. The magnet valve 28 is provided with a port 48, which port, when the valve is in the position shown in the drawing, and the train in restricted territory, registers with the port 46 in which is connected the reservoir pipe 47 and the port 49 in which is connected the blow down pipe 50, therefore it will be seen that the 125 130

blow down valve 21 will operate when the magnet valve 28 is in deenergized position and the train is in restricted territory, and when not in restricted territory, and the 5 magnet energized the valve port 48 will only register with the port 49 in the valve casing 29, consequently passage of air from the blow down reservoir pipe 47 to the blow down valve 21 will be stopped.

10 From the above it will be seen that a speed control valve having indicating or signalling means in connection therewith is provided for train control systems, which may be easily and quickly applied to conventional forms of control systems without materially modifying the construction thereof, and without varying the normal operations of said systems. It will also be seen that the control and indicating or signalling 15 means will indicate to the engineer when he has attained the prescribed speed within the restricted area, and will also indicate to him that an increase of speed will automatically set the brakes, however the engineer will have a free range of control below the prescribed restricted speed. By providing the adjusting bolts 18, it will be seen that the valve 21 may be adjusted minutely and accurately, and at the same 20 time the port 41 may be placed at various distances in relation to the port 44 in which the pipe 45 is connected for allowing a slight range of movement before an automatic operation.

25 35 The invention having been set forth what is claimed as new and useful is:—

1. The combination with a train control system having a magnet valve and a speed governor, of valve means operated by said speed governor and cooperating with ports in communication with ports in the magnet valve and forming means whereby when a predetermined speed is substantially obtained a signal will be given and upon exceeding the predetermined speed brakes will be set.

2. The combination with a train control system of the character set forth and having a magnet control valve, speed control mechanism, a reservoir pipe line leading to a blow down valve, a feed pipe line, said magnet valve being provided with ports registering with ports in the reservoir pipe line and the feed pipe line when the magnet is deenergized, a speed control valve, a port carried by said speed control valve and registering with spaced ports in the feed pipe line at a predetermined speed, said feed pipe line terminating in a signaling device, a second port carried by the speed valve, a relay and protection valve pipe line leading to the atmosphere, said second port carried by the speed valve registering with a port in the relay and protection valve pipe line and overlapping a second port in said relay and

protection valve pipe line, whereby upon an increase of speed both of said last named ports will register with the second mentioned port in the speed valve.

3. The combination with a train control 70 brake system of the character described and comprising a magnet control valve having spaced ports, a speed governing device, of means for limiting the speed of a train and indicating the attainment of substantially 75 a predetermined speed, said means comprising a speed control valve having spaced ports, a blow down reservoir pipe line having ports of communication with one of the spaced ports of the magnet valve, a feed pipe 80 line having ports of communication with the other port of the magnet valve and ports of communication with one of the ports of the speed control valve, a relay and protection valve pipe line leading to the atmosphere 85 and having ports, one of which registers with one of the ports of the speed control valve at substantially a predetermined speed and the other port positioned whereby upon an increase of speed both of said ports will 90 register with the speed control valve port.

4. The combination with a train control system of the character described and comprising a speed governor and a magnet valve, of a speed control valve controlled by the governor, said magnet valve and speed control valve cooperating whereby upon the attainment of a predetermined speed a signal will be continuously given and upon exceeding the predetermined speed the train 100 will be stopped.

5. The combination with a train control system of the character described comprising a speed governor and a magnet valve and into ports of which valves a feed line 105 discharges through spaced ports, a blow down reservoir pipe line discharging into a port of the magnet valve through spaced ports and leading to the blow down valve, said speed control valve having its ports positioned whereby upon the attainment of a predetermined speed the feed valve line will operate a signal through one port and upon increased speed above the predetermined speed air will be exhausted from a relay 110 and protection valve line.

6. The combination with a train control system of the character described having a speed governor, of a speed control valve co-operating with spaced ports of a feed valve 120 line leading to a signalling device and a relay and protection valve line having spaced ports and leading to the atmosphere and forming means whereby upon attainment of a predetermined speed a port of the valve will register with the spaced ports of the feed valve line and a port of the speed valve will register with one of the ports of the relay and protection valve line and upon a further movement of the valve will register 125 130

with both ports of the relay and protection valve line.

7. The combination with a train control system of the character described, of a governor controlled speed controlling valve having spaced ports cooperating with spaced ports in a feed valve line and a relay and

protection valve line and forming means whereby at a predetermined speed the feed valve line will be open and upon an increase ¹⁰ of speed the relay and protection valve line will be open.

In testimony whereof I affix my signature.

GEORGE W. DODGE.
